Inventor:
James R. Elliott,
By Robert Burns, Atty.

UNITED STATES PATENT OFFICE.

JAMES R. ELLIOTT, OF DENVER, COLORADO.

VENTILATOR.

1,134,259.

Specification of Letters Patent.

Patented Apr. 6, 1915.

Application filed April 11, 1912. Serial No. 889,945.

To all whom it may concern:

Be it known that I, JAMES R. ELLIOTT, a citizen of the United States of America, and a resident of Denver, in the county of Denver, State of Colorado, have invented certain new and useful Improvements in Ventilators, of which the following is a specification.

This invention relates to the controllable type of ventilators or registers employed for ventilating and heating purposes, and has for its object to provide a simple and efficient structural formation and combination of parts, adapted to afford a minimum amount of obstruction when used as a floor ventilator or register and which in addition provides for free and ample delivery of air with a ready and convenient control of such delivery, all as will herein-
20 after more fully appear.

In the accompanying drawings: Figure 1, is a vertical section on line $x-x$, Fig. 2, of a ventilator embodying the present improvements. Fig. 2, is a horizontal section of the same on line $x'-x'$ Fig. 1.

Similar reference numerals indicate like parts in both views.

Referring to the drawings, 1 represents an annular ring or bushing provided with 30 an outwardly extending marginal top flange 2 adapting it to fit a circular orifice formed for its reception in the floor or other like portion of a building or structure.

3 are orificed lugs on the flange 2 for the passage of attaching screws, when the ventilator is applied to a wood floor or the like.

4 are orificed lugs on the inner surface of the ring 1 for the passage of anchor bolts 5 when the ventilator is applied to a concrete
40 floor or the like.

6 are guide ears on the inner surface of the ring 1 for guiding engagement with the guide stems of the hereinafter described adjustable cover member.

45 7 is a screw-threaded central hub integrally connected to the ring 1 by radial arms 8, as shown.

9 is a depending yoke formed integral with the arms 8 aforesaid, and provided at bottom
50 with a centrally arranged guide hub 10.

11 is the adjustable cover member above referred to, and which in the present construction is of a mushroom shape, the crown of which is centrally depressed to form a

cavity 12 for the reception of the operating 55 wing nut hereinafter described, the purpose being to avoid a projection of said wing nut above the top surface of the cover member as an obstruction.

13 are a series of vertical guide stems de- 60 pending from the cover member 11 aforesaid, and having guiding engagement with the guide ears 6 before described, to insure rectilinear movement of said cover member in its adjustments.

14 is a vertically arranged screw-thread arbor journaled centrally in the bottom wall of the cavity 12 of the cover member 11 by a reduced neck as shown, and provided at its upper end with a winged operating nut 15 70 disposed within said cavity as shown.

16 is a guide stem depending from the lower end of the arbor 14, and having guiding engagement in the guide hub 10 of the yoke 9, aforesaid.

Having thus fully described my said invention, what I claim as new and desire to secure by Letters Patent, is:

1. A register, comprising a frame, a closure, a screw journaled at its opposite extremities 80 in parts of said register and connecting said closure with said frame, the register having a threaded opening intermediate the journaled extremities of said screw, the screw passing through said threaded opening and 85 co-operating with the threads of the latter when the screw is turned for moving the closure to and from the said frame.

2. A register, comprising a frame adapted to surround the heat or ventilating 90 opening, a closure, a screw connecting said closure with said frame, the register having parts in which the opposite extremities of said screw are journaled, the register having a threaded opening intermediate the journaled extremities of said screw, the screw 95 passing through the said threaded opening and co-operating with the threads of the latter when the screw is turned to move the closure to and from the said frame, and 100 guide rods connecting said closure with the frame for preventing turning of the closure.

3. A register, comprising a frame, a closure, a screw connection between said frame and the closure, one extremity of the said 105 screw having a reduced extension, the frame having a centrally located member in which the said reduced extension of said screw is

2
journalized, and guide rods for said closure, the said guide rods preventing turning of the said closure.

4. A register, comprising a frame adapted to surround a heat or ventilating opening, a closure, a screw connection between said frame and the closure, one extremity of the said screw having a reduced part, the frame having a centrally located member 10 and the said reduced part of said screw be-

ing journaled in said centrally located member and guide rods for preventing turning of the closure.

Signed at Denver, Colorado, this 2nd day of April 1912.

JAMES R. ELLIOTT.

Witnesses:

ABE GRABER,

ARTHUR C. HORDISON.
